UNITED STATES PATENT OFFICE.

JOHN A. MCGAHY, OF NEW YORK, N. Y.

FIRE-ALARM.

SPECIFICATION forming part of Letters Patent No. 573,903, dated December 29, 1896.

Application filed April 30, 1896. Serial No. 589,811. (No model.)

To all whom it may concern:

Be it known that I, JOHN A. MCGAHY, of the city, county, and State of New York, have invented certain new and useful Improvements in Fire-Alarms; and I do hereby declare that the following is a full, clear, and exact description of the same, reference being had to the accompanying drawings, making a part of this specification, in which—

10 Figure 1 is a diagrammatic view of a fire-alarm apparatus made according to my invention. Fig. 2 is a detail viewed at right angles to Fig. 1. Figs. 3 and 4 are detail views, on a larger scale, showing modifications of 15 one of the elements entering into combinations included in my invention.

This invention relates to the automatic detection of fires, conflagrations, &c., in dwellings, factories, and other buildings, and it 20 comprises certain new and useful combinations of parts whereby I provide a self-acting fire-detector which, through suitably-arranged electric wires, makes known both by 25 visual and audible signals the occurrence of the fire and its locality.

A is an electromagnet supported upon a metal bracket B. At the upper part of the latter is an arm B', which provides a bearing for the pivot a of an armature C. This armature has at its upper end a horizontal spur b, which carries a weight c, which tends to throw the armature away from the electric magnet. Near its free extremity the armature has a notch or shoulder d, below which 35 is an inclined surface a'. A battery B², which may be of any suitable kind, is provided to supply electric energy for the operation of the apparatus.

D is a metallic bar pivoted at one end, as at 40 b', and at the other carrying a tag e, which should project upward at an angle to the bar, substantially as shown in Fig. 1. In this bar is a slot c' through which projects the lower portion of the armature, the parts being so 45 proportioned that when the bar is raised to lift the tag into its non-signaling position behind a plate or partition A' or other hiding or obscuring device, as represented in Fig. 1, the shoulder d of the armature catches under the 50 stop f', formed by the end of the slot c, as the armature is swung outward by the weight c, thereby retaining the bar and the tag in their

raised position so long as the armature is kept away from the electromagnet. Arranged below the bar is a contact-piece E.

From the one pole g of the battery B² to the contact-piece E extends a wire F. From the same pole g of the battery extends another wire G, hereinafter more fully described. From the opposite pole h of the battery extends a wire H, which is connected with the one end of the coil of the electromagnet. The opposite end of said coil is connected to a wire I, which, as hereinafter explained, operates in direct conjunction with the wire G. From the same pole h of the battery extends a wire K, which connects with the usual or any suitable mechanism of an electric bell or audible signal L. From the bar D extends a wire M, which connects with the said bell or audible signal, operating in connection with the wire K to provide the requisite circuit through the said audible signal apparatus. In this wire M is provided a suitable switch C², by means of which, when desired, such circuit may be made or broken.

The two wires G and I are brought together, as at m. For convenience in placing the wires in the house or structure where the fire-alarm is to be employed each of these wires may pass 80 to suitable binding-posts a² b², after which they are brought parallel to each other and confined together to form a cable, as at N. This cable is extended through or around or 85 in any desired manner within the room or place in which it is intended to detect fire or undue rise of temperature, should such occur. The two wires G and I, where thus brought together to form the cable N, are insulated from each other, as represented, for 90 example, in Fig. 3, in which the insulating material of each is shown at f² and the external strata holding them together at g². They are so constructed that upon an undue rise of temperature the insulation from each 95 other will disappear, so that an electric current will circuit direct from the one wire to the other at the place where the insulation between them is destroyed.

The character of the wires G and I may be 100 varied somewhat, according to the judgment of the constructor. As shown in Fig. 3, they are copper wires, each insulated with any suitable fusible or combustible material. As

such insulating materials are well known in the art, none need be here specifically described. Upon the ignition, combustion, or fusion of the insulating-coverings of the two wires they come into contact with each other in such manner as to permit the transit of the current from one to the other. As shown in Fig. 4, one of the wires, for instance, G, is of copper, while the other, I, is of fusible metal.

- 10 The two are insulated from each other by any suitable material *n*, interposed between them, and the two are bound together by an insulating-covering *r* common to both. Upon the occurrence of fire along the cable N when thus formed, the fusible metal of the wire I melts and runs into contact with the wire G, thus establishing electrical communication between them.

Normally the bar D and, of course, the tag *e* are in their elevated position, as shown in full outline in Fig. 1. The wires G and I being insulated from each other and lying normally disconnected there is no circuit through the battery and there is of course no expenditure of energy from the latter. When, however, the two wires G and I of the cable N are connected by an elevation of temperature, as described, a circuit is closed through the electromagnet, which, putting the latter in 25 operation, attracts the armature C and thereby withdraws its support from the bar D and permits the latter, together with its tag *e*, to descend into view. As the tag descends the bar D or the tag, as the case may be, comes 30 against the contact-piece E and thereby completes a circuit through the bar D, the contact-piece E, the wires F and K, and the wire M, which actuates the bell or other audible 35 signaling device, so that by the means described the occurrence of a fire sufficient to es-

tablish electric connection between the wires G and I of the cable N is simultaneously signaled audibly and visually by the descent of the tag *e* and by the automatic sounding of the bell or like audible device consequent upon the fall of the tag or visual signaling device.

What I claim as my invention is—

1. The combination with an electric circuit, means for closing the same from an elevation of temperature, and a battery for supplying the current, of an electromagnet, the armature having a counterweight, *c*, and a notch or shoulder, *d*, the bar, *D*, having the tag, *e*, and slot, *c'*, a contact-piece, *E*, a wire, *F*, connecting said contact-piece with one pole of the battery, a bell or audible signaling device, and wires, *M*, and, *K*, the one extended from the bar, *D*, and the other from the battery, and both to the audible signal, substantially as and for the purpose herein set forth.

2. The combination with the electromagnet, *A*, armature, *C*, having bent arm, *b*, and counterweight, *c*, the bar, *D*, having shoulder, *d*, and carrying tag, *e*, a contact-piece, *F*, a battery, *B*², and a bell or audible signal *L*, of wires, *I*, and, *G*, united to form cable, *N*, the wire *F'*, uniting the contact-piece with the battery, and the wire, *H*, extending from the battery to the coil of the magnet, and the wires, *M*, and, *K*, extended to the audible signal from the bar, *D*, and the battery respectively, all substantially as and for the purpose herein set forth.

JOHN A. MCGAHEY.
